UNITED STATES PATENT OFFICE.

WILLIAM L. KEENE, OF WATERVILLE, MAINE.

DRAFT REGULATOR.

Application filed February 3, 1921. Serial No. 442,178.

To all whom it may concern:

Be it known that I, WILLIAM L. KEENE, a citizen of the United States, residing at Waterville, in the county of Kennebec and 5 State of Maine, have invented certain new and useful Improvements in Draft Regulators, of which the following is a specification.

My said invention relates to a draft regulator for controlling the fire used in operating steam generators, thus determining the steam pressure in such generators and regulating the heat given off by them in operation. Such draft regulators are peculiarly 10 adapted for use in connection with steam or hot water heating systems for dwellings, but their utility is not limited thereto.

It is an object of my invention to provide a draft regulator which may be controlled 20 by the pressure of the steam but which is operated by means preferably mechanical entirely independent of the steam pressure, whereby a very small variation of pressure may operate to open or close the damper.

25 A further object of my invention is to provide a thermostat which may be controlled by the temperature of the air in a room to be heated and which forms an auxiliary controlling means in addition to the pressure control heretofore mentioned.

30 Another object of my invention is to provide means whereby the damper may be closed when the steam reaches the desired pressure regardless of the temperature of 35 the atmosphere in rooms to be heated. In this way overheating of dwellings is prevented.

Another object is to provide a device of 40 the character described in which the controlling mechanisms may be set so as to be inoperative and when they are so set the draft will be cut off.

45 A further object of my invention is to provide a device of this kind which can be operated either by the steam pressure alone or by steam pressure and room heat combined.

Referring to the accompanying drawings which are made a part hereof and on which

similar reference characters indicate similar 50 parts,

Figure 1 is an elevation of my device, showing the parts in one of their operative positions, the relative position thereof in a heating system being shown in Figure 6, 55

Figure 2, a plan of the same, certain portions being omitted,

Figure 3, a detail of a circuit breaker and stop,

Figures 4 and 5 are details of parts shown 60 in Figures 1 and 2, and

Figure 6, an elevation showing the device in its relation to a furnace.

In the drawings reference character 10 indicates a furnace of a steam or hot water 65 heating system, which is connected to a pressure operated device 11, here shown as of the diaphragm type to be operated by steam. In use any device which will produce satisfactory results may be substituted 70 therefor such for instance as that in which water acts on a thermostatic tube to vary the length of the same according to the temperature.

A lever 12 is attached to the pressure device 11 in the usual way and this lever has connected thereto a rod 13 carrying a series of collars 14, 15 and 16. The rod is guided by an opening in the support A and a bracket 17 projecting from the main frame 75 B.

The operating mechanism for the damper 18 comprises a rock arm 19 moved in one direction by a weight 20 and in the other by a chain 21 connected to a crank 22 having a plurality of openings therein for adjustment of the chain. The crank 22 is mounted on a shaft 24 carrying at its opposite end a crank 23 connected by a chain 21' to the furnace door 23' and this shaft has fixed 85 thereon a pinion 25 meshing with a gear 26 on a shaft 27. The shaft 27 has a sprocket gear 28 over which passes a sprocket chain 29 having at one end a weight 30 and having near the other end an adjustable stop 31 90 which may take the form of a bolt passing through a link of the chain 29 and having a nut threaded on one end thereof. The

sprocket is connected to the gear 26 by a pawl 32 engaging a ratchet 33 and intended to permit the sprocket to rotate freely in one direction. In this manner the sprocket is 5 adapted to be driven in one direction by the weight 30 until its limit of movement is reached and the same may readily be re-set by a pull on the opposite end of the chain. Adjacent the pinion 25 a gear 34 is fixed 10 to shaft 24 and this gear engages a pinion 35 on a shaft 36 which also carries a gear 37 engaging a pinion 38 on a shaft 39. Shaft 39 has a gear 40 meshing with a pinion 41 on a shaft 42, the latter carrying a fan brake 15 43 of the usual type. All these shafts are journaled in the frame work B and the shaft 42 projects through the frame work and carries at its end a pin 44 comprising the end portion of a piece of spring wire wound 20 about the shaft.

Adjacent the pin 44 is a pivoted armature 45 having a projecting portion forming a stop by means of which the armature acts as a detent to engage the pin to prevent rotation of the shaft 42. A pair of electro-magnets 46 are attached to the frame to move the armature in one direction and a rod 47 pivoted at one end to the armature is impelled in a direction to withdraw the armature from the electro-magnets by a light spring located in a casing 48. The shaft 24 in addition to the parts hereinafter enumerated carries a disk 49 having a portion of its periphery formed of insulating material 50. This disk normally holds the armature out of engagement with pin or finger 44 and has a notch adapted to be engaged by the rod 47 under pressure of its spring. When this notch is positioned as shown in Figure 40 1 the armature may advance into position to be engaged by the pin.

Shaft 24 also carries a second disk 51 having a notch 51' in its periphery as clearly shown in Figure 1 and the disks are to be 45 so adjusted that the latter notch is a little over 90° distant from the first. Disk 51 is adapted to control the position of two levers 52 and 53. These levers act as detents to stop rotation of the gearing 50 by the weight motor, by engagement with pin 44, the upper lever having a hook to engage the pin and the lower lever having an enlarged end portion which the pin may strike. The levers are adapted to be held 55 in inoperative position by the disk 51, but reach a position where they may engage pin 44 when the projection or riser on either lever drops into the notch 51' on disk 51. Lever 52 is also adapted to be lifted out of 60 action by a pin 15' projecting from the collar 15. A spring pressed pin 14' extends upwardly from collar 14 into engagement with lever 53 to lift the same when the notches of disk 51 are properly positioned.

Lever 53 carries a spring 54 which constitutes one member of a circuit closer, the other member being an adjustable pin 55 mounted in a bracket 56 on support A. A second circuit breaker is located at one end 70 of the frame and comprises a member 57 pivoted at 57' and contacting with the head of pin 58 said member having a handle 80. A 75 slidable member 59 pivoted to the movable element 57 has at its further end an enlarged head with an upwardly extending portion 60 adapted to engage the lower end of the armature and draw the detent 47 away from disk 49.

At any convenient place, as on the wall of a room to be heated is placed a thermostat 80 comprising a base 61 carrying a thermostatic member 62 having a bent portion extending from its point of attachment to the base and terminating in a straight portion. Near the end of the straight portion is a contact member having a head 64 in alignment with its pivot for varying its position, and carrying an adjusting screw 63 for determining the limit to which the room temperature may fall. The member 62 is so made as to contract when the temperature falls whereby it may make contact with the adjusting screw 63. When this thermostat is not to be used the circuit breaker at 57 may be operated to break the circuit and retract the armature. Another circuit breaker is provided in juxtaposition to the sprocket chain and comprises a lever 65 pivoted on an insulated bolt 66 of conducting material and adapted to contact with another insulated bolt 67 of similar material on the frame. The lever 65 carries a pin 71 extending beneath a pawl 72 also pivoted on screw 66. The rod 68 extends downward from lever 65 and carries at the lower end a block 69, forced away from support A by a spring 70. The block 69 and spring 70 form a resilient buffer for chain 29 which passes through an opening in the block, the block being engaged by a stop 31 on the chain as the chain nears the end of its travel. This compresses the spring and lifts rod 68 and the outer end of lever 65, thus breaking the circuit between parts 65 and 67. At the same time the downward movement of pin 71 lowers the pawl 72 which, upon engagement with the notch in disk 73 on shaft 24, stops the rotation of the various shafts of the device. This prevents overtravel of the chain whereby it might run off the sprocket, and the interruption of the circuit prevents waste of current. A wire 74 connects the screw 67 to one terminal of the room thermostat. A second wire 75 extends from screw 67 to a screw 76 on the main frame which supports at its other end the casing 48. This casing is electrically connected to disk 49 by a leaf spring 77.

If desired I may provide a latch at 77,

here shown as slidable, adapted to engage under a collar 78 on rod 13 and hold the entire device out of action.

5 *Operation.*

The position of the parts for operating under control both of the pressure device 11 and the room thermostat 61 is shown in the drawings and particularly in Figure 1. In 10 this figure the current may pass from the battery to the room thermostat, thence by wire 74, screw 67, pivoted arm 65, screw 66, wire 75, screw 76, casing 48, spring 77, and disk 49 to shaft 24, and from this shaft 15 through disk 51, detent 53, spring 54, pin 55 and bracket 56 to wire 78. From wire 78 current passes to electro-magnets 46 thence to pin 58 and circuit closer 57 and back to the battery by wire 79. With the parts in 20 the position shown the damper is closed and the furnace door which moves as the damper is also closed and the device is subject to variations in room temperature and also to the action of pressure device 11 in the following 25 manner; when the thermostat 11 draws the rod 13 down sufficiently to close the circuit at 54, 55 and withdraw detent 53 from notch 51', the shaft 24 becomes subject only to the electrical mechanism controlled by the room 30 temperature, i. e., it is held from rotation by the detent on armature 45. The damper cannot be opened until the room temperature has fallen sufficiently to close the circuit at 63 when the electro-magnet will be 35 energized and will retract armature 45 and its detent, thus permitting the weight 30 to act as a motor to operate the shaft 42 through the train of gearing until notch 51' comes in position for engagement by the 40 riser on detent 52, i. e., until the shaft 24 has made a half revolution and the damper is open, when pin 44 is engaged by detent 52 to stop the movement of the regulator. It 45 is to be noted that when the crank 22 points downward and the damper is open, the insulating segment 50 is underneath the leaf spring 77, this being to prevent waste of current, since at this time the temperature of the room may be so low as to close the circuit at 63 although the damper is open.

The damper being open will remain so until the thermostat 11 raises the rod 13; i. e., until the temperature of the hot water heating system, or the temperature and pressure 55 of the steam heating system, or like controlling feature has risen sufficiently to actuate the thermostat as indicated, whereupon detent 52 is raised by pin 15' and the weight motor comes into action again to rotate the shaft 24 and close the damper, the disk 51 now holding the armature away from pin 44 by means of rod 47 and the circuit being broken at 50. Rotation ceases when notch 51' comes over the stop-lug on detent 53,

which is forced upward by spring-pressed pin 14' and the end of the detent now engages pin 44 to halt the action of the weight motor.

When detent 53 engages pin 44 disk 49 has revolved so far that rod 47 is on the verge of dropping into the notch on the disk. When now the rod 13 falls, due to decreasing steam pressure or the like, so far as to remove detent 53, it simultaneously permits shaft 24 to rotate until rod 47 falls into its notch, drawing armature 45 into position to engage pin 44 and stop such rotation, and also closes the circuit of the room thermostat at 54, 55. This completes the cycle.

Assuming that the device is to be operated by steam pressure alone the circuit may be broken by actuation of the circuit closer 57. Thereupon, the damper being in its closed position, as shown in Figure 1, will remain so until the action of the pressure device 11 lowers the rod 13 due to the lowered temperature of the water (or other controlling condition) to such a degree that the lever 53 falls so far as to release the pin 44 from its engagement with the end of the lever whereupon weight motor 30 drives the shaft 42 through the train of gearing until the disk 51 has rotated so far that the lever 52 is permitted to fall by engagement of its lug with notch 51' whereupon the pin 44 is caught by the hook on detent 52 and held against rotation, the arm 22 pointing downward from shaft 24 and the damper 18 being in open position. The parts will now stay in this relation while the fire builds up and the steam pressure increases until the pin 15' lifts detent 52 to release pin 44 when the weight 30 resumes its operation and turns arm 22 to the position shown in Figure 1, lever 53 being actuated by the spring pressed pin 14' to enter its lug in the notch of disk 51 whereby its outer end is positioned to engage the pin 44 and hold it until the pressure device 11 again lowers the rod 13. The lug of the detent which is out of action rides on the periphery of the disk 51 whereby the detent is restrained from engaging the pin 44.

The purpose of the spring pressed pin 14' is to provide lost motion connection between 115 rod 13 and detent 53 to prevent interference by the lower detent with the movement of rod 13 to release detent 52.

Among the special advantages of my device may be mentioned the fact that it is not dependent on the steam pressure for actuation of the damper, the weight motor being arranged to actuate the same positively and the steam pressure serving merely to actuate a trigger-like device which controls the action of the weight motor; that since it does not depend on steam pressure or water heat or the like it will respond to small changes

in temperature; that due to its construction the damper will be closed when the device is put out of operation as an entirety; and finally that overheating is effectively prevented by the arrangement for closing the damper when the steam pressure or water heat is sufficient whether the room temperature has by that time risen to the desired height or not.

10 Various modifications of my device or of parts thereof will occur to those skilled in the art, and I do not limit myself to the precise form shown in the drawings, nor to the particular use described, the scope of the invention being defined in the appended claims.

As an example of such modifications the 20 thermostatic element may consist of a rod or tube projecting into the furnace itself or into the fluid heated by the furnace, whether same be water or air. The thermostatic controlling means may operate on a damper within the smoke pipe or a check draft damper or it may operate on a valve controlling ingress of heated air or steam or any device equivalent to any of the above means. Various other motors, e. g., spring motors, may be substituted for the weight motor shown.

25 Having thus fully described my said invention what I claim as new and desire to secure by Letters Patent, is:

1. In combination, a pressure controlled device, a rod extending upwardly therefrom, 30 a damper, a rotary shaft to move the damper, a motor for rotating the shaft, means for locking the shaft to hold the damper open or closed comprising a pair of detents and means on said upwardly extending rod for moving said detents, substantially as set forth.

2. In combination, a shaft, means tending to rotate the same in one direction, a temperature-controlling device connected to the 45 shaft and adapted to be operated by rotation of the shaft, means to lock the device and its driving means in a predetermined position, a disk on said shaft to hold said locking means inoperative and a pressure controlled 50 means co-operating with the disk to control the locking means, substantially as set forth.

3. In combination, a shaft, means tending to rotate the same in one direction, a temperature-controlled device connected to the 55 shaft, means to lock the shaft in predetermined positions comprising a second shaft geared to the first, and having a finger extending therefrom, a pair of detents adapted to engage the finger alternately, and means to control the detents including means attached to the boiler, substantially as set forth.

4. In combination, a shaft, means tending to rotate the same in one direction, a temperature-controlling device connected to the

shaft, means to lock the shaft in predetermined positions comprising a second shaft geared to the first, and having a finger extending therefrom, a plurality of detents adapted to engage the finger alternately, and means on the first shaft for holding the detents out of engagement at predetermined times, substantially as set forth. 70

5. In combination, a shaft, means tending to rotate the same, in one direction, a temperature-controlling device connected to the shaft, means to lock the shaft in predetermined positions comprising a second shaft geared to the first, and having a finger extending therefrom, a plurality of detents 75 adapted to engage the finger alternately, means on the first shaft for holding some of the detents out of engagement at predetermined times, and an electro-magnet adapted to move one of the detents out of engagement with the finger at another time, substantially as set forth. 80

6. In combination, a shaft, means tending to rotate the same, in one direction, a temperature-controlling device connected to the 90 shaft, means to lock the shaft in predetermined positions comprising a second shaft geared to the first, and having a finger extending therefrom, a plurality of detents adapted to engage the finger alternately, an electro-magnet for disengaging one of said 95 detents from the finger, a thermostat for controlling its action, and means connected to the boiler whereby the remaining detents may be released, substantially as set forth. 100

7. In combination, a shaft, means tending to rotate the same in one direction, a temperature-controlling device connected to the shaft, means to lock the shaft in predetermined positions comprising a second shaft 105 geared to the first, and having a finger extending therefrom, a pair of detents adapted to engage the finger alternately, means to control the detents including a pressure operated device, a rod attached thereto and having a fixed abutment and a yieldable abutment for engagement with the respective detents, and a notched disk on the first shaft adapted to co-act with said rod to control said detents, substantially as set forth. 110

8. In combination, a shaft, means tending to rotate the same in one direction, a temperature-controlling device connected to the shaft and adapted to be operated by rotation of the shaft, a second shaft geared to the 120 first and having a projecting pin, detents to engage said pin alternately to prevent rotation of the shaft, a disk on the first shaft having a notch for alternately engaging projections on the respective detents, and a pressure controlled device co-operating 125 with the disk to control the locking means, substantially as set forth.

9. In combination, a shaft, means tending to rotate the same in one direction, a temper-

- ature-controlling device connected to the same comprising a shaft, a finger thereon, a shaft and adapted to be operated by rotation of the shaft, a second shaft geared to the first and having a laterally projecting pin, 5 detents to engage said pin alternately to prevent rotation of the shaft, a disk on the first shaft having a notch for alternately engaging projections on the respective detents, a rod having a rigid finger to engage one detent and a yieldable finger to engage the other, and means controlled by the heating medium co-operating with the disk to control the locking means, substantially as set forth. 10
- 15 10. In a heating system, a shaft, means tending to rotate the same in one direction, a temperature-controlling device connected to the shaft and adapted to be operated by rotation of the shaft, a second shaft geared 20 to the first, a plurality of locking means whereby said second shaft and its connected mechanism may be locked in predetermined positions, means controlled from a source of heat for releasing the one of said locking 25 means, and means controlled by the temperature of a room for releasing another locking means, substantially as set forth.
11. In combination, a shaft, means tending to rotate the same in one direction, a 30 temperature-controlling device connected to the shaft and adapted to be operated by rotation of the shaft, a second shaft geared to the first, means whereby said second shaft and its connected mechanism may be locked 35 in predetermined positions, auxiliary locking means acting on said second shaft in another position and temperature-controlled means for releasing both sets of locking means, substantially as set forth.
- 40 12. In a heating system, a shaft means tending to rotate the same in one direction, a temperature-controlling device connected to the shaft and adapted to be opened and closed by rotation of the shaft, a second 45 shaft geared to the first, a plurality of locking means whereby said second shaft and its connected mechanism may be locked in predetermined positions, means controlled from a source of heat for releasing the one of said 50 locking means, an armature connected to the second locking means, and a thermostat electrically connected to operate said armature, substantially as set forth.
13. In combination a temperature-controlling device and means to operate the 55 same comprising a shaft, a finger thereon, a plurality of holding devices for the finger, means to retract one of the holding devices comprising an electro-magnet, a thermostat 60 in circuit therewith, and means to move another holding means toward the finger and thereby break said circuit, substantially as set forth.
14. In combination a temperature-controlling device and means to operate the 65
- same comprising a shaft, a finger thereon, a plurality of holding devices for the finger, means to retract one of the holding devices comprising an electro-magnet, a thermostat 70 in circuit therewith, and means to move another holding means toward the finger and thereby break said circuit, substantially as set forth.
15. In combination, a temperature-controlling device, and means to operate the same comprising a weight motor, and a train of gearing, means for engaging a shaft of 75 said gearing to stop the movement thereof, means to engage another shaft to lock the motor against rotation, said means being normally held out of operative position and being restored to action by said motor near the limit of its travel, substantially as set forth. 80
16. A heating system comprising a temperature-controlling device, a furnace, and means for operating said device comprising a thermostat adapted to be placed in a room 90 to be heated, and a second thermostat connected to the furnace and adapted to operate the temperature controlling device independently of the first thermostat, and means whereby the first thermostat may be rendered inoperative, substantially as set forth. 95
17. A heating system comprising a temperature-controlling device, a furnace, and means for operating said device comprising a thermostat adapted to be placed in a room to be heated, and a second thermostat connected to the furnace and adapted to control said device in conjunction with the first or independently thereof, substantially 100 as set forth.
18. In a heating system, a furnace, a damper, means for actuating the damper, means to lock the damper in open or closed position, a pressure device connected to the furnace, mechanical means connected to the pressure device for controlling the locking means, and means whereby the pressure device may be put out of action, substantially 110 as set forth.
19. In a heating system, a furnace, a 115 damper, means for actuating the damper, means to lock the damper in open or closed position, a pressure device, a vertically movable rod connected to the pressure device for controlling the locking means, a collar on the rod and means to hold the rod in elevated position whereby the damper controlling mechanism is rendered inoperative, substantially as set forth. 120
20. In a heating system, a furnace, a 125 damper, means for actuating the damper comprising a rotating shaft, a pair of detents adapted to engage the shaft in alternation to lock the damper in open or closed position, a pressure controlling device con- 130

ected to the furnace, a rod on the pressure device adapted to release the detents from said shaft and means whereby the rod may be held in inoperative position, such means 5 permitting the damper actuating mechanism to close the damper, substantially as set forth.

21. In a heating system, a furnace, a damper, means for actuating the damper, 10 a plurality of detents to lock the damper in predetermined positions, a room thermostat, an electro-magnet controlled thereby for releasing one of said detents, a furnace pressure device, a rod actuated by the pressure device for controlling the remaining detents, 15 means for locking said rod in inoperative position whereby said rod also breaks the circuit of said electro-magnet and permits the damper actuating means to close the 20 damper, substantially as set forth.

22. In combination, a temperature controlling device and means to operate the same comprising a shaft, a finger thereon, means for holding the finger against rotation, an electro-magnet for retracting said holding means and a circuit closer adapted to deenergize said electromagnet and simultaneously withdraw the holding means, substantially as set forth.

30. 23. In a heating system, a furnace, a damper, means for actuating the damper and the furnace door, means to lock the damper and the furnace door in open or closed position, pressure controlled device 35 connected to the furnace, means connected to the pressure device for controlling the locking means, and means whereby the thermostat may be put out of action substantially as set forth.

40. 24. In a heating system, a furnace, a damper, means for actuating the damper and the furnace door, means to lock the damper and the furnace door in open or closed position, a thermostat, a vertically 45 movable rod connected to the thermostat for controlling the locking means, a collar on the rod and means to hold the rod in elevated position whereby the controlling means for the damper and the furnace door 50 is rendered inoperative.

25. In a heating system, a draft-regulating device, mechanical means for opening and closing said device, connected to the furnace for normally controlling said mechanical means, a room thermostat supplementing the action of the second said means to prevent opening of the draft until the room temperature falls to a predetermined extent, an electric circuit for the room thermostat, and means actuated by the first-named thermostat for making and breaking said circuit, substantially as set forth.

26. In a heating system, a furnace, a draft regulating device thereon, and means governing said device comprising a rotary shaft

connected to the draft controlling device, a weight motor for rotating the shaft, temperature-controlled means to put the motor into and out of action, and means to engage the shaft to stop the operation of the controlling devices with the draft off as the weight motor approaches its limit of action, substantially as set forth.

27. A heating system comprising a furnace, draft regulating means therefor, a motor for operating said draft regulating means, means controlled by the heating medium to govern the motor, temperature controlled means adapted to lock the motor whereby the motor cannot operate to increase the draft until acted upon by the temperature controlled means, substantially as set forth.

28. A heating system comprising a furnace, a damper, a motor for opening and closing the damper and the furnace door, means connected to the furnace to mechanically operate to cause the motor to close the damper, temperature controlled means adapted to lock the motor in such position whereby the motor cannot operate to open the damper until acted upon by the temperature controlled means, substantially as set forth.

29. A heating system comprising a furnace, draft regulating means therefor, a motor for operating said draft regulating means, pressure controlled means to govern the motor, temperature controlled means adapted to lock the motor whereby the motor cannot operate to increase the draft until acted upon by the temperature controlled means, substantially as set forth.

30. A heating system comprising a furnace, a damper, a motor for opening and closing the damper and the furnace door, a temperature controlling device, pressure controlled means connected mechanically to the furnace and the motor whereby upon reaching a predetermined pressure the said pressure controlled means also operating the motor to place the motor entirely under the control of the temperature controlling device when and only when the pressure has dropped to a predetermined point, said temperature controlling device then being adapted to operate the motor to open the furnace door and damper, substantially as set forth.

31. A heating system comprising a furnace, a damper, a motor for opening and closing the damper and the furnace door, a temperature controlling device, pressure controlled means connected mechanically to the furnace and the motor whereby upon reaching a predetermined pressure the said pressure controlled means also operating the motor to place the motor entirely under the control of the temperature controlling device when and only when the pressure has

dropped to a predetermined point, said temperature controlling device then being adapted to operate the motor to open the furnace door and damper, and means where-
5 by the temperature controlling device may be eliminated leaving the motor at all times under the control of the pressure controlling means, substantially as set forth.

In witness whereof, I have hereunto set my hand and seal at Waterville, Maine, this 10 twenty-fifth day of January, A. D. nineteen hundred and twenty-one.
